UNITED STATES PATENT OFFICE.

HERBERT W. OWEN, OF DOVER, NEW HAMPSHIRE, ASSIGNOR TO DRAPER COMPANY,
OF HOPEDALE, MASSACHUSETTS, A CORPORATION OF MAINE.

SPINNING-FRAME.

1,041,665.

Specification of Letters Patent.

Patented Oct. 15, 1912.

Application filed November 22, 1911. Serial No. 661,797.

To all whom it may concern:

Be it known that I, HERBERT W. OWEN, a citizen of the United States, and a resident of Dover, in the county of Strafford and 5 State of New Hampshire, have invented certain new and useful Improvements in Spinning-Frames, of which the following is a specification.

This invention relates to spinning machines, and has particular reference to mechanism connected with the ring rail to effect 10 the changes in its vertical position.

When doffing, the ring rail is usually moved to a position below its lowest extreme 15 when traversing, to facilitate access to the bobbin. Then the machine is run slowly, as by working the shipper lever back and forth, so as to give slack yarn to enable the full bobbins to be removed, and to furnish the 20 slack yarn to be fastened ready for the operation on the new bobbins. Then when the new bobbins are all in place and the machine is starting, the doffer puts his foot on the usual foot piece attached to the lever of the 25 lifter mechanism and works the said lever up and down a few times to cause a few turns of the yarn to be coiled on the bases of the bobbins, starting the travelers and aiding any kinks in the yarn to pass through 30 the travelers. In starting the machine after any stoppage, it is customary to go through the same operation which is aptly called "jiggling". Without considerable practice, this "jiggling" is liable to be excessive, and 35 furthermore it requires considerable physical effort.

The object of my present invention is to provide means whereby this "jiggling", or series of short traverses, may be imparted 40 to the ring rail whenever desired, by power, thus avoiding the expenditure of physical effort by the doffer, and causing such short traverses to be uniform and with a predetermined degree or amount of motion.

To these ends, the invention consists in the construction and combination of parts, substantially as hereinafter described and claimed.

Of the accompanying drawings,—Figure 50 1 is a front elevation of so much of a spinning machine as is necessary to illustrate my invention in one of its embodiments. Fig. 2 is a detail end view, looking from the left of Fig. 1.

Similar reference characters indicate the same or similar parts in both the views.

The spindle rail 15 supports the spindles in the usual manner, and the ring rail 17 carries rings for travelers, said ring rail being supported upon lifter rods. To avoid unnecessary drawings, only one spindle is shown, as at 16, one ring 18, one traveler 19, and one lifter rod 20. The complete machine has a plurality of lifter rods each actuated in an upward direction by a rocker 21 under the influence of weight 22. The rocker 21 has an arm 23 from which a link 24 extends to another rocker arm for another lifter rod. The rocker arm is provided with the usual segment 25. This segment 25, in 70 a well known type of spinning frame, is connected by a chain with the builder motion. In the present drawings, such builder motion and the chain therefrom to the rocker arm are omitted to avoid confusion. 75 As shown in the accompanying drawings, however, there is a chain 26 connected at one end to the segment 25 from which it passes under a sheave 27 carried by a bracket 28 that is supported by the end frame of the 80 machine. From said sheave 27 the chain passes upwardly and over a sheave 29 carried by one end of a lever 30 which is pivoted at 31 on a pin or stud shaft projecting from the frame of the machine, the other end of 85 said lever 30 carrying a roll 32. From the sheave 29 the chain 26 passes downwardly and is secured to a rotary stud 33 as by being passed through a transverse aperture in said stud and the end of the chain having a 90 cotter ring 34. The stud 33 is rotatively mounted in the end frame of the machine and has a hand wheel 35 in a position readily accessible to the doffer. In Fig. 2 the front roll shaft 36 is illustrated as constructed and in the usual position therefor, said shaft having a gear 37 that is driven by the usual gear of the machine. Connected 95 to rotate with said shaft as by being secured to the spokes of the wheel 37 is a cam 38. This cam is illustrated as circular in form but eccentric to the axis of the shaft 36 with which it rotates.

It is to be understood of course that the shaft 36, and of course the cam 38 also will 105 be constantly rotating at a uniform speed whenever the machine is spinning. The lever 30 is held normally in substantially the

position shown by full lines in Fig. 2 by suitable means such as a spring 39 connected at one end to said lever 30 and at the other end to a suitable stationary point. This, 5 or any mechanical equivalent therefor is for the purpose of normally keeping the roll 32 sufficiently spaced from the cam 38 to prevent the lever 30 from being actuated by said cam. Whenever the doffer or other operator desires that the ring rail shall be 10 "jiggled" or have imparted thereto a series of short traverses, he simply rotates the hand wheel 35 in the direction of the arrow in Fig. 2 so as to wind up the chain 15 upon the rotary stud 33 until by doing so the resulting pull upon the chain will cause the roll 32 to bear against the cam 38. The hand wheel is simply held with sufficient firmness so that the oscillations of the lever 20 30 under the influence of the rotating cam will not unwind the chain from the rotary stud, but will cause the sheave 29 to exert a pull in the bight or loop of chain passing over it, such pull being then transmitted 25 to the portion of the chain which passes around the sheave 27 to the rocker arm 23. Owing to the sheave 29 being in a bight of the chain, the amount of motion imparted to the rocker arm will be double the amount 30 of motion that is imparted to the sheave 27 by the cam 38 acting upon the roll 32 at the other end of the lever 30, consequently the amount of eccentricity of the cam 38 need be but very slight.

35 As long as the hand wheel 35 is held in the manner described, the ring rail will have imparted thereto a series of short traverses, with the same results that have heretofore been obtained by the doffer pressing his foot 40 upon the foot piece 40 carried by the rocker 21. This foot piece 40 is shown in Fig. 1 of the drawings for the purposes of illustration in connection with the above description, but it will be understood of course, that 45 with my improvement, such foot piece 40 will not be necessary for use to impart the short traverses. However, it is desirable to still retain such foot piece for other uses, such as the carrying of the ring rail down 50 for doffing purposes.

When the doffer releases the hand wheel, the spring 39 immediately causes the lever 30 to move to a position to carry the roll 32 away from operative position relatively to the cam 28.

55 It will be understood that the cam 38 constitutes a power-operated actuator which is of course structurally independent of the builder motion of the machine, and that the lever 30 constitutes a movable member 60 which is normally separated from said cam or actuator but is adapted to be manually shifted to position where its roll 32 will engage said cam or actuator so as to result in motion being transmitted through the chain 65 to the ring rail.

I claim:—

1. A spinning machine having means for mechanically traversing the ring rail, said means including a power-operated actuator, 70 a movable member normally separated from said actuator and adapted to be manually shifted to position to be operated by said actuator, and connections between said movable member and the ring rail to transmit 75 motion to the latter, said actuator and connections being structurally independent of the builder motion of the machine.

2. A spinning machine having a cam, a lever normally out of position to be operated 80 by the cam, manually operable means for shifting the lever to position to be actuated by the cam, and connections between the lever and ring rail for causing the latter to be traversed by said lever.

85 3. A spinning machine having a cam, a lever having a roll at one end adapted to contact with said cam, a sheave at the other end of the lever, a chain passing over said sheave and connected at one end to the 90 rocker arm of the ring rail lifter mechanism, and means for taking up the other end of said chain.

In testimony whereof I have affixed my signature, in presence of two witnesses.

HERBERT W. OWEN.
